[57]

ABSTRACT

Individual supply pipes connect each of the intake ports of the engine to an air-fuel distributor system which includes an intake air manifold. A source of liquid fuel maintained at substantially constant pressure is connected to the air-fuel distributor system. A plurality of individual adjustable throttle valves are disposed respectively within the supply pipes and are interconnected with one another for joint movement. The speed (and power) of the engine is varied by manually varying the limit of adjustability of the air-fuel distributor system. The throttle valves are automatically (as contrasted with manually) adjusted by means of a vacuum controller and throttle valve actuator which utilizes after-throttle vacuum as an operating or power source to adjust the throttle valves to maintain a substantially constant manifold vacuum.

CARBURETION SYSTEM

CROSS-REFERENCE TO RELATED APPLICATION

This application is a continuation-in-part of my co-pending application Ser. No. 800,689 filed Feb. 19, 1969, now abandoned, which in turn is a continuation-in-part of my application Ser. No. 608,887 filed Jan. 12, 1967, now U.S. Pat. No. 3,475,011.

BACKGROUND OF THE INVENTION

This invention relates generally to the field of carburetion systems and more particularly to individual intake port carburetion systems.

My present invention differs from the invention set forth in said application Ser. No. 608,887 in several respects, one of which involves the control of the throttle valves. In the system disclosed in application Ser. No. 608,887 the throttle valves located in the individual supply pipes and interconnected for joint movement are adjusted manually to control engine speed whereas in my present invention the throttle valves are actuated by an automatic throttle control which positions the throttle valves in accordance with the levels of vacuum before and after the throttle valves and the changes in these levels of vacuum which occur in response to variations in the primary and secondary air flow rates, the operation of the engine and the adjustment of the air-fuel distributor system.

Thus the invention disclosed in my application Ser. No. 608,887 involves the manual adjustability of the throttle valves by the engine operator to change the speed of the engine. In the present invention the throttle valves are controlled automatically to maintain a predetermined level of vacuum in the engine manifold and the engine operator, in order to vary engine speed, manually varies the limit of adjustability of the air-fuel distributor system.

The air-fuel distributor system of the present invention includes air and fuel metering elements which are urged toward open positions by pressure differential resulting from reduced pressure created by air flowing past the air meter element. The rate of opening of the air and fuel metering elements, up to the operator-selected limit, is determined by the ability of the engine to accelerate and ingest the air and fuel mixture under the prevailing road load and operating conditions and the reaction of the automatic throttle valve positioning device.

The engine operator can manually selectively increase and decrease the limit of adjustability to which the air and fuel metering elements may be opened. The actual opening of the air and fuel metering elements to the selected limits of adjustability is regulated by the ability of the engine to accelerate as provided for by the automatically actuated throttle valves and the prevailing engine operating conditions, whereas closing of the air and fuel metering elements is directly controlled by the operator by decreasing the air and fuel metering elements limit of opening to accomplish either a reduction in engine speed or to proceed down to an idling or shutdown condition. The fuel supply is cut off in the latter position to prevent evaporation of fuel.

The automatic throttle valve actuator of the present invention, in taking the direct control of the throttle valves away from the operator and in tending to maintain a predetermined level of vacuum in the manifold, provides optimum use of an individual intake port carburetion system for the control of exhaust emissions. Fuel cut off at shutdown also eliminates air pollution resulting from evaporation of fuel.

The present automatic throttle valve control system ensures simultaneous air and fuel metering changes in advance of throttle valve changes, as contrasted with the throttle valve control system of said application Ser. No. 608,887. By ensuring that air and fuel metering changes precede throttle valve position changes the present invention substantially eliminates hesitation and misfiring of the engine during acceleration and deceleration, again reducing exhaust emission.

The present invention also serves to maintain a constant fuel rate and fuel-air ratio (and therefore constant engine

power) when the operator maintains the limit of adjustability of the air and fuel metering elements at a stationary position. As a consequence, when the vehicle is being driven along an undulating road, the throttle valves automatically tend to open in response to a tendency of the engine to slow down when the vehicle is on an upgrade, and automatically tend to close when the vehicle is on a downgrade. As a result, less physical and mental effort is required of the operator to maintain a steady road speed.

In addition, the present invention can be associated with an automatic car speed control to provide a control characteristic which is more desirable than that which is available from conventional carburetor or fuel injection systems where fuel rate is a function of engine speed, increasing with downhill or reduced load conditions, and decreasing with uphill or increased load conditions. The improved control characteristic of the present invention results from an automatic control of the throttle valves working in conjunction with the air and fuel metering elements to maintain a constant power with varying road load conditions rather than the unstable decrease in power with increasing load that causes a reduction in engine speed or, conversely, an increase in power with increased engine speed resulting from a reduction in road load on a downgrade. The operator of a vehicle which incorporates the individual intake port carburetion system of the present invention will enjoy a more stable control of engine power and resulting better speed control in addition to an optimum control of exhaust emissions.

SUMMARY OF THE INVENTION

The present invention may be briefly summarized as comprising an individual intake port carburetion system for delivering an air-fuel mixture to the intake ports of a multi-cylinder internal combustion engine comprising a plurality of supply pipes connected respectively to the intake ports of the engine, an intake air manifold connected to the supply pipes for receiving and directing secondary air to the supply pipes, throttle valves in the supply pipes interconnected for joint movement, means including a plurality of primary air-fuel mixture conduits for delivering to each of said supply pipes downstream of said throttle valves a mixture of primary air and liquid fuel including means for connection to a source of liquid fuel under pressure, means connected to said last named means and responsive to the vacuum condition of the air in said manifold for varying the flow rate of liquid fuel and the primary air-fuel ratio in said conduits in response to variations in manifold vacuum and means connected to said throttle valves and responsive to variations in manifold vacuum for adjusting the throttle valves to maintain the level of vacuum in said manifold at a substantially constant value.

Objects of the invention include, among others, greater operating efficiency, a reduction in harmful exhaust emissions and easier and more stable engine control and operation.

BRIEF DESCRIPTION OF THE DRAWING

FIG. 1 is an elevational view of an individual intake port carburetion system constructed in accordance with the principles of the present invention and mounted on a multi-cylinder internal combustion engine, only a portion of the engine being illustrated for the sake of simplicity.

FIG. 2 is a top plan view of the system shown in FIG. 1.

FIG. 3 is a sectional view of an air-fuel distributor of the present invention taken along lines III-III of FIG. 2 and a schematic view of fuel supply circuitry connected to the air-fuel distributor.

FIG. 4 is a view of a portion of the carburetion system taken substantially along lines IV-IV of FIG. 2.

FIG. 5 is a sectional view of an automatic throttle valve actuator taken along lines V-V of FIG. 2.

FIG. 6 is a fragmentary elevational view of another embodiment of a fuel meter element of the present invention.

DESCRIPTION OF THE PREFERRED EMBODIMENT

Referring to FIGS. 1 and 2 an individual intake port carburetion system constructed in accordance with the principles of the present invention is indicated generally at reference numeral 10 and is shown mounted on a multi-cylinder internal combustion engine 11, having multiple air intake ports as indicated at reference characters A, B, C & D. A piston-cylinder arrangement is associated with each of the intake ports A, B, C & D, as will be understood by those skilled in the art. Although the principles of the present invention are of applicability in connection with any multi-cylinder engine, the embodiment thereof shown in FIGS. 1 11 and 2 is more particularly adapted for a six-cylinder engine, although only four of the corresponding intake ports have been illustrated.

The carburetion system 10 may be more particularly characterized as comprising an intake air manifold 12 and supply pipes 13a-13d which communicate each of the intake ports A-D individually with the intake air manifold 12.

Throttle valves indicated at reference characters 14a-14d correspond in number to and are disposed respectively within the supply pipes 13a-13d. In the embodiment illustrated throttle valves 14a-14d are of the butterfly type and are mounted respectively for pivotal movement on rotatable shafts 15a-15d which are journaled in the walls of their respective supply pipes 13a-13d. Shafts 15a-15d are connected together for joint movement with one another by means of a mechanical linkage including lever arms 16a-16d and a throttle bar 17 to which the arms 16a-16d are pivotally connected.

Also connected to shaft 15d for joint rotation therewith is another lever 18 to which is connected a throttle arm 19. The arm 19 is pivotally connected to a piston rod 20 of an automatic throttle valve actuator indicated generally at reference numeral 21 for joint reciprocatory movement therewith.

The actuator 21 comprises an end wall 22 from which the piston rod 20 extends, and as the arm 19 is moved by the piston rod 20 away from the end wall 22 the individual throttle valves 15a-15d are simultaneously moved toward a more open position. Conversely, as the arm 19 is moved in the direction of the end wall 22, the throttle valves 15a-15d are simultaneously moved toward a more closed position.

Referring to FIG. 3, the air manifold 12 comprises an air inlet opening 23 through which air enters the manifold 12. That portion of the air which enters the manifold 12 and which flows directly from the manifold through the supply pipes 13a-13b to the intake ports A-D is referred to herein as "secondary air."

An air-fuel distributor, indicated generally at reference numeral 24, is associated with the air manifold 12 and comprises first and second sections 26 and 27, the two sections being held together in fixed assembly by suitable fastening devices such as a plurality of threaded bolts one of which is indicated at reference numeral 28. The second section 27 comprises a fragmental cylindrical imperforate and impervious sleeve 29 forming an annular chamber 30 which communicates with the interior of the air intake manifold 12 and a perforated and pervious cylindrical inner sleeve 31 arranged concentrically within the sleeve 29 and having an array of small bores or air passageways 32 extending radially therethrough and arranged circumferentially therearound. An imperforate end portion 33 of the inner sleeve 31 extends through a radial imperforate wall member 34 which interconnects the outer and inner sleeves 29 and 31 adjacent their outer ends. Another radial wall 34a interconnects the inner and outer sleeves 29 and 31 adjacent their inner ends. The air inlet opening 23 is located in an open end of the inner sleeve 31. Thus all of the air which flows into the air manifold 12 must flow through the air inlet opening 23, through the imperforate end portion 33 of the inner sleeve 31, then into the interior or hollow of the sleeve 31, then through the air passageways 32 into the annular chamber 30, and then into the interior of the air manifold 12. It is therefore apparent that all of the air ingested into the en-

gine 11 flows through the air inlet opening 23. This includes the 1"secondary air" which flows into the air manifold 12 and through the individual supply pipes 13a-13d to the intake ports A-D.

5 The first section 26 of the air-fuel distributor 24 may be characterized as comprising a cylindrical body 35 and a tubular member 36 extending axially therefrom and connected thereto by means of a plurality of threaded rods one of which is indicated at reference numeral 37. Extending axially through the body 35 are a plurality of air passageways, one of which is indicated at 38, which air passageways are radially angularly spaced with respect to the axis of the body 35. Disposed within each of the air passageways 38 is a reduced diameter rod 39, one end of which is connected to an air meter element or baffle 40 and the opposite end of which is connected to a cup-shaped member 41. The air meter element 40 comprises a tubular wall 42, an end wall 43 and a radially outwardly extending wall 44, an outer peripheral wall 46 thereof being in slidable and relatively substantially air-sealing relation with an inner wall 47 of the perforate sleeve 31. The walls 42, 43 and 44 are imperforate and therefore in the position thereof shown in FIG. 3 the air meter element 40 substantially precludes any flow of air through the air inlet opening 23 and into the air manifold 12 since all of the air passageways 32 of the inner sleeve 31 are "closed" to the air inlet opening 23, that is, are separated therefrom by the imperforate air meter element 40. Therefore, unless the air meter element 40 is moved leftwardly from the position thereof shown in FIG. 3 and into the interior of the inner sleeve 31 to uncover or open at least some of the air passageways 32, air is prevented from flowing from the air inlet opening 23, into the interior of the inner sleeve 31 and through the air passageways 32 into the interior of the air manifold 12. The rod 39, the air meter element 40 and the inverted cup-shaped member 41 are interconnected for joint movement and are biased in a rightward direction toward the position thereof shown in FIG. 3 by means of a coil spring 48 which is bottomed at one end 49 on the end wall 43 of the air meter element 40 and at an opposite end 50 on a bottom wall 51a of an annular groove 51 formed in a radial wall 52 of the cylindrical body 35.

The coil spring 48 merely provides a slight rightward bias to the air meter element 40 so that it can properly function as an air meter and move in response to the difference in pressure on the upstream and downstream sides thereof in order to regulate the rate of air flow in the intake ports A-D of the engine 11 as a function of the flow rate of air entering the intake air manifold 12 through the air inlet opening 23. Thus the coil spring 48 merely provides a bias to the air meter element 40 sufficient to move the same to the closed or rightward position thereof shown in FIG. 3 before the engine is cranked and before air is induced into the intake air manifold 12 through the air intake opening 23. When the engine is being cranked, however, the force and the spring 48 (and the mass of the air meter element 40 and the rods 39 if the arrangement of the carburetion system 10 in the engine 11 is such that the movement of air meter element 40 is vertical rather than horizontal as in the embodiment illustrated herein) provides a predetermined "minimum vacuum" condition which must exist before air is able to flow into the manifold 12. This minimum vacuum is predetermined to be slightly less than the "manifold vacuum" of the system 10, which is the level of vacuum in the manifold 12. Manifold vacuum is, of course, maintained at a substantially constant level throughout the entire operating range of the engine 11, as will be explained fully hereinafter.

Under normal operating conditions the air meter element 40 will be urged leftwardly to the limit of its movement by virtue of the pressure differential across the upstream and downstream sides thereof. Since this pressure differential is the difference between atmospheric pressure and manifold vacuum, and since manifold vacuum will (unless the engine is being stalled due to overload) always be greater than said minimum vacuum (that vacuum level required to move the air

meter element 40 leftwardly) there is always some excess force tending to urge the air meter element 40 leftwardly, even when it is moved to its limiting position.

Also formed in the cylindrical body 35 is a fuel inlet port indicated at reference numeral 53 communicating with a liquid fuel chamber 54, which chamber 54 communicates with a primary air chamber 56 through a reduced diameter interconnecting passageway 57.

The fuel inlet port 53 receives liquid fuel under pressure from a fuel supply system indicated schematically at reference numeral 58. The fuel supply system 58 may be more particularly characterized as comprising a fuel tank 59, a fuel pump 60 and a pressure regulator 61 through which liquid fuel under pressure is delivered to port 53 through a fuel supply pipe 62. The pressure regulator 61 preferably maintains the fuel being delivered to the fuel inlet port 53 at a constant pressure and a bleed return line 63 interconnects line 62 with the fuel tank to provide a fuel bleed back to the tank during shutdown of the engine 11, thus relieving fuel pressure in the air-fuel distributor 24.

Slidably disposed within the fuel chamber 54, the primary air chamber 56 and the interconnecting passageway 57 is a fuel metering element which, in the embodiment illustrated, comprises an elongated rod indicated at reference numeral 64. An end portion 66 of the rod 64 extends through a threaded bore 67 formed in an end wall 68 of the inverted cup-shaped member 41 and terminates at end portion 69 which projects beyond a nut 70 connecting the rod 64 and the cup-shaped member 41 in fixed assembly.

A lower portion 64a of the rod 64 which, in the position thereof shown in FIG. 3, extends from a lower wall 71 of the primary air chamber 56, through the reduced diameter passageway 57 and into the fuel chamber 54, is slightly tapered in a rightward direction. By virtue of this taper, flow of fuel from the fuel chamber 54 into the primary air chamber 56 is precluded in the position of the fuel meter element 64 shown in FIG. 3. However, as the air meter element 40 is moved leftwardly in response to an increasing flow of air into the manifold 12 through the air inlet opening 23 and, correspondingly the fuel meter element 64 is moved leftwardly (as the same is viewed in FIG. 3) the tapered portion 64a gradually increasingly communicates the fuel chamber 54 and the primary air chamber 56 to provide a corresponding increase in the flow rate of fuel into the primary air chamber 56. The liquid fuel which enters the primary air chamber 56 from the fuel chamber 54 by virtue of the leftward movement of the fuel meter element 64 mixes with air, referred to herein as "primary air," which enters the primary air chamber 56 through a series of primary air passages 72 formed in circumferentially spaced relation in a tubular wall member 73 of the body 35. Primary air is received by the passages 72 from a chamber 75 which is formed between an outer surface 74 of the wall member 73 and an inner surface 76 of the inverted cup-shaped member 41.

The admixture of primary air and fuel is delivered to each of the intake ports A-D through a plurality of primary air-fuel mixture outlet passageways, one of which is indicated at reference numeral 77, formed in the body 35 of the air-fuel distributor 24 and extending in angularly spaced and communicating relation with the primary air chamber 56. The primary air-fuel outlet passageways 77 correspond in number to the number of intake ports A-D of the engine 11 and communicate respectively with such intake ports A-D through a corresponding plurality of primary air-fuel conduits, portions of which are indicated at reference numerals 78 in FIGS. 1 and 2 and one of which, corresponding to intake port C, being indicated at reference numeral 78c.

The primary air-fuel conduits 78 terminate respectively at open ends 79a-79d, which are located within the supply pipes 13a-13 at a point downstream of their corresponding throttle valves 14a-14d.

Also disposed within the first section 26 of the air-fuel distributor 24 is a cylindrical piston member 80 which is divided

by a partition wall 81 into first and second chambers 82 and 83. Chamber 82 communicates with atmosphere through a slot 84 formed in a tubular extension 86 of the first section 26 and chamber 83 communicates with and is maintained in the same vacuum condition as the primary air chamber 56 (which is substantially equal to manifold vacuum). The piston member 80 is slidable within the tubular extension 86 and the partition wall 81 thereof provides a movable stop against which the end 69 of the fuel meter element 64 is biased into abutting engagement during normal running operation of the engine 11.

The piston member 80 is axially adjustable within the tubular extension 86 and may be manually selectively positioned therewithin by the engine operator by virtue of a rod 87 which extends through the slot 84 and which is connected in fixed assembly both to the piston member 80 and to a flexible cable 88 which may be manually actuated by any suitable means such as, for example, a foot pedal indicated schematically at reference numeral 89 which is biased by means of a spring 89a.

It will be appreciated that movement of the piston member 80 in a leftward direction (as the same is viewed in FIG. 3) does not have the effect of positively moving the air meter element 40 and the fuel metering element 64 leftwardly toward more open positions thereof, but merely provides a stop against which the leftward movement of air and fuel elements 40 and 64 is limited.

On the other hand, rightward movement of the piston member 80 (and more particularly of the partition wall 81 thereof) has the effect of positively moving the air and fuel elements 40 and 64 rightwardly toward more closed positions thereof.

Referring to FIGS. 1, 2 and 5, the automatic throttle valve actuator 21 is pneumatically operated and regulates the movement of the throttle valves 14a-14d to maintain a substantially constant predetermined level of vacuum in the intake air manifold 12. To this end the actuator 21 moves the piston rod 20, the arm 19 and the throttle valves 14a-14d in response to variations in the level of vacuum within the air manifold 12.

The actuator 21 comprises a cylindrical body 90 forming a chamber 91 therewithin and end caps 92 and 93 forming chambers 94 and 96 respectively therewithin facing the chamber 91. Disposed movably within the chamber 91 is a piston member indicated generally at reference numeral 97. The piston 97 may be more particularly characterized as comprising a radial wall member 98 having a first motive surface 99 on one side thereof and a second motive surface 100 on the opposite side thereof. Motive surface 99 is in communication with the chamber 94 and motive surface 100 is in communication with chamber 91, chambers 94 and 91 being separated by a flexible diaphragm 101, the peripheral portion of which is claimed stationarily to the body 90 by means of a plurality of fastening devices as indicated at 102 and a central portion 103 of which is connected in fixed assembly to the radial wall 98 for joint movement therewith.

Extending axially from the motive surface 100 is an enclosed tubular member 104 arranged concentrically with the axis of the cylindrical body 90 for reducing the effective area of the motive surface 100 to that area which lies between a cylindrical wall 106 to the tubular member 104 and an inner wall 107 of the body member, which extends in concentric relation to the cylindrical wall 106.

A second flexible diaphragm 108 is clamped stationarily at its peripheral portion to the cylindrical body 90 and a central portion thereof is clamped in fixed assembly to a radial wall 109 of the tubular extension 104, an outer surface 110 of the radial wall 109 being in communication with chamber 96. An oversize bore 111 formed in an end wall 112 of the cap 93 maintains chamber 96 at atmospheric pressure and received therewithin the piston rod 20 which is connected by means of a threaded end 113 thereof to the piston member 97 for joint movement therewith.

A bore 114 extends through an outer wall 116 of the cylindrical body 90 and communicates with chamber 91. A conduit 117 is connected at one end 118 to bore 114 and is connected at an opposite end 119 to a vacuum controller indicated generally at reference numeral 120 (FIG. 4). Another bore 121 extends through an end wall 122 of the cap 92. A conduit 123 connects at one end 124 to bore 121 and at an opposite end 126 to the air-fuel distributor 24 for communicating the chamber 30, and thus the interior of the intake air manifold 12, with the chamber 94, thus maintaining the level of vacuum in chamber 94 equal to the level of vacuum which obtains in the intake air manifold 12.

Referring to FIG. 4 the vacuum controller 120 may be further characterized as comprising a body member 120' having a series of aligned chambers 120a, 120b and 120c formed therewithin adjacent one another. A cylindrical sleeve 125 is disposed in chambers 120a and 120b and is ported as at 127 to communicate a chamber 128 formed within the hallow sleeve 125 with a bore 129 formed in the body 120' and communicating with the end 119 of the conduit 117.

Another port 130 formed within the sleeve 125 communicates chamber 128 with chamber 120b as well as with a bore 131 formed in the body 120' and connected to one end 132 of a conduit 133, an opposite end 134 of which conduit 133 is connected to conduit 123.

Axially slidably disposed within chamber 128 of the sleeve 125 is a plunger 136 having a reduced diameter portion 137 formed centrally thereof, an enlarged diameter portion 138 formed at one end of the reduced diameter portion 137 and a pair of lands 139 formed in an opposite end of reduced diameter portion 137. A lower end 140 of the plunger 136 extends into chamber 120c and is connected in fixed assembly to a central portion of a flexible diaphragm 141, the peripheral portions of which are clamped stationarily to the body 120' to partition chamber 120c into a pair of mutually isolated chambers 142 and 143.

The body 120' of the vacuum controller 120 is bored as at 144, which bore 144 communicates with chamber 128 as well as with one end 146 of a conduit 147 as shown also in FIGS. 1, 2 and 3. An opposite end 148 of conduit 147 connects to a feeder conduit 149, to which a plurality of after-throttle vacuum conduits 150a-150d are connected. As indicated at reference character 151c the opposite ends of each of the conduits 150a-150d open into each of their respective supply pipes 13a-13d at a point downstream of their respective throttle valves 14a-14d, that is, between the throttle valves 14a-14 and the intake ports A-D.

As used herein "after-throttle" vacuum is the level of vacuum in the supply pipes 13a-13d downstream of the throttle valves 14a-14d and constitutes the vacuum condition at the intake ports A-D. "Before-throttle" vacuum is the level of vacuum which obtains upstream of the throttle valves 14a-14d and is virtually the same as manifold vacuum, the level of vacuum which exists in the air intake manifold 12, and can be used interchangeably with that term herein.

The vacuum controller 120 also includes a coil spring 152 which surrounds the tubular sleeve 125. A top end 153 of the spring 152 bottoms on a shoulder 154 facing chamber 123 and a bottom end 156 bottoms on the central portion of the flexible diaphragm 141. A bore 157 extends through a bottom wall 158 of the vacuum control body 120' to communicate chamber 143 with atmosphere.

By virtue of the bore 131 and the conduit 133 the chamber 120b and a top side 159 of the diaphragm 141 communicate with the intake air manifold 12 and are therefore subjected to "manifold vacuum." By virtue of bore 157 a bottom side 160 of the diaphragm 141 communicates with atmosphere, and by virtue of bore 144 and conduits 147, 149 and 150a-150d, the upper end of chamber 128 is maintained at a vacuum level which is equal to "after-throttle" vacuum or the average of the levels of vacuum which obtain in the supply pipes 13a-13d downstream or on the intake port sides of the throttle valves 14a-14.

Thus the vacuum condition to which the upper side 159 of flexible diaphragm 141 is subjected is manifold or before-throttle vacuum, whereas the vacuum condition to which the upper end of chamber 128 is subjected is after-throttle vacuum. It is appreciated that in conventional carburetion systems in which a single butterfly throttle valve is employed upstream of the air intake manifold, the terms "manifold vacuum" and "after-throttle vacuum" are often used synonymously. Within the context of the present invention, however, in which individual throttle valves are employed for each intake port downstream of the air intake manifold, the terms "manifold vacuum" and "after-throttle vacuum" connote different vacuum levels, or levels of vacuum which obtain at different locations in the carburetion system, and are to be defined herein in the manner set forth above.

Chamber 94 of the automatic throttle valve actuator 21 is maintained at manifold vacuum, whereas chamber 91 is maintained at a vacuum level determined by virtue of the operation of the vacuum controller 120. Thus the conduit 117, which communicates the vacuum controller 120 with chamber 91, may be subjected to manifold vacuum, by virtue of conduit 133, or to after-throttle vacuum, by virtue of conduit 147, or to a vacuum level which is between manifold vacuum and after-throttle vacuum, the piston or plunger 136 moving reciprocally to communicate the bore 129 either with bore 131 or bore 144.

The spring 152 of the vacuum controller 120 and the diaphragm 141 are sized, constructed and arranged so as to 30 vary the position of the plunger 136 in the sleeve 126 in response to variations in manifold vacuum.

Assume, for example, in the illustrated embodiment of the invention, that it is desired to maintain manifold vacuum, that is, the level of vacuum within the air intake manifold 12, at 35 about 8 inches H₂O during normal operation of the engine 11. When a manifold vacuum of 8 inches (of water) obtains, the pressure differential across the opposite sides 159 and 160 of the diaphragm 141 (the difference between atmospheric pressure and actual manifold vacuum) is sufficient to urge the diaphragm 141, and thus the plunger 136, upwardly to the "centered" position thereof shown in FIG. 4. In this position the bore 129 communicates with neither the bore 131 nor the bore 144. If the manifold vacuum were to rise above 8 inches (water used throughout) to, say, 10 inches, the diaphragm 141 would be moved upwardly, thereby moving the plunger 136 upwardly from its centered position, whereby bore 129 will communicate with bore 131 to subject chamber 91 of the throttle actuator 21 to manifold vacuum. If the manifold vacuum were to drop below 8 inches to, say, 6 inches, the diaphragm 141 would be moved by the spring 152 downwardly from its centered position shown in FIG. 4. This downward movement of diaphragm 141 as well as of plunger 136 would have the effect of communicating bore 129 with bore 144 to subject chamber 91 of the throttle actuator 21 to after-throttle vacuum.

After-throttle vacuum is, of course, during normal operation of the engine 11, always considerably greater than the manifold vacuum by virtue of the relatively substantial pressure losses of the air as it passes across the individual throttle valves 14a-14b. In the embodiment illustrated, for example, it is assumed that after-throttle vacuum is always at least slightly more than twice as great as manifold vacuum, although it will be appreciated that a vacuum of 16 inches of water (two times manifold vacuum of 8 inches) at the intake ports of a conventional internal combustion system is relatively small, and most engine designs will produce a vacuum condition of about 5-10 inches of mercury at the intake ports.

Thus, the after-throttle vacuum of at least more than twice manifold vacuum being assumed herein for the illustrated embodiment of the engine 11 is relatively small. This ensures that a suitable control vacuum sufficient to open the valves 14a-14 is available whenever necessary.

The minimum level of after-throttle vacuum necessary to 75 open the valves 14a-14d is preferably selected relative to

manifold vacuum so that it can be produced or rapidly recovered in the event that the operator should suddenly greatly depress the foot pedal 89. In conventional carburetion systems attempts at rapid acceleration result momentarily (until engine speed increases substantially) in poor air-fuel ratio, poor combustion and high toxic emission. According to the principles of the present invention an attempt at rapid acceleration by rapidly depressing the foot pedal 89 has the effect of rapidly reducing manifold vacuum from 8 inches of water to say, 6 inches of water. This initiates the automatic opening of the throttles at a controlled rate such that the throttle valves will not open faster than engine speed can increase sufficiently to increase and maintain an after-throttle vacuum greater than its minimum level, for example, 16 inches of water.

Thus, because of this automatic control of throttle opening during acceleration a more uniform fuel-air ratio results, along with better combustion and substantial decrease in toxic emission.

In any event, after-throttle vacuum is utilized in the present invention as a source of a power in assisting in the operation of the throttle valve actuator 21, since it is always greater than manifold vacuum, the vacuum which is intended to be regulated so as to be maintained substantially at a predetermined level. The principal purpose of maintaining the manifold vacuum at a constant level, of course, is to provide a substantially constant fuel-air ratio under all operating conditions for optimum operation of the air meter.

The desired amount by which after-throttle vacuum exceeds manifold vacuum during normal operation of any given engine determines the selection of the relative sizes of the motive areas of the throttle actuator 21. For example, in the illustrated embodiment of the invention after-throttle vacuum (by virtue of the sizing and configuration of the supply pipes 13a-13bq, the throttle valves 14a-14d) is always at least twice as great as manifold vacuum except during a stall or crank condition of the engine. For that reason the throttle valve actuator 21 is constructed so that the area of motive surface 99 (which is always subjected to manifold vacuum) is approximately twice as great as the area of motive surface 100 (which may be subjected to manifold vacuum or to after-throttle vacuum or to an intermediate vacuum). The motive surface 110 is always subjected to atmospheric pressure.

In the circumstances, if atmospheric pressure was to obtain in chambers 91, 94 and 96 of the automatic throttle valve actuator 21 (the pressure of the air in the closed interior of tubular member 104 has no effect whatsoever) the piston member 97, and thus the piston rod 20, would remain stationary. If a vacuum condition were then to obtain in chambers 91 and 94, the piston member 97 would move leftwardly, (as viewed in FIG. 5) to cause the piston rod 20 to move the throttle valves 14a-14 toward the closed positions thereof, unless the level of vacuum in chamber 91 were at least twice as great as the level of vacuum in chamber 94, in which event the piston member 97 would be moved rightwardly to cause the piston rod 20 to move the throttle valves 14a-14d toward the open positions thereof. The above described action occurs simply as a result of the differences in the areas of motive surfaces 99, 100 and 110 which are in turn selected as a consequence of the minimum factor by which after throttle vacuum exceeds manifold vacuum in any given engine design. This can be further explained by assuming that the area of motive surface 99 is equal to A, and that the areas of motive surfaces 100 and 110 are equal to A/2. Further assume that the pressure (or vacuum) to which surfaces 99 is subjected is P_1 , and that the pressures to which areas 100 and 110 are subjected are P_2 and P_3 respectively.

Therefore, if the pressures are such as to maintain the piston member 97 in a balanced condition, then

$$P_1A = P_2A/2 + P_3A/2$$

$$P_1A = (P_2 + P_3)/2$$

$$P_1 = P_2 + P_3/2$$

$P_2 = 2P_1 - P_3P_3$, of course, is atmospheric pressure. Now if P_2 is equal to 2 times $P_1 - 14.7$ psia, then the piston 97 is in a balanced condition. Therefore, if P_1 is 1 psia less than atmospheric (or 13.7 psia), the piston 97 will be balanced if P_2 is 2 psia less than atmospheric (or 12.7 psia.). Or, if P_1 is 2 psia less than atmospheric (or 12.7 psia), the piston 97 will be balanced if P_2 is 4 psia less than atmospheric (or 10.7 psia.).

In terms of vacuum, the piston 97 will be balanced so long as the vacuum level in chamber 91 is twice as great as the vacuum level in chamber 94 (since the area of motive surfaces 100 and 110 are one-half the area of motive surface 99). If, however, the vacuum level in chamber 91 falls below two times the vacuum level in chamber 94, the piston 97 will move leftwardly as viewed in FIG. 5. If the level of vacuum in chamber 91 rises above two times the level of vacuum in chamber 94, the piston 97 will be moved rightwardly.

It is not necessary that the relationship of the areas of the motive surfaces 99, 100 and 110 which obtains in the illustrated embodiment be utilized in all instances. In fact, if engine design does not result in an after-throttle vacuum of at least two times manifold vacuum, then the area of motive surface 100 can be increased vis-a-vis the area of motive surface 99 until a ratio is obtained which is suitable for the reduced after-throttle vacuum.

Furthermore, it is not essential that motive surface 110 be subjected to atmospheric pressure and the entire rightward end of the piston 97 could of course merely be subject to the same pressure as chamber 91. However, since the illustrated embodiment of the engine 11 provides an after-throttle vacuum of at least two times manifold vacuum under ordinary operating conditions, the area of motive surface 100 can be reduced to one-half of the area of motive surface 99, providing smoother operation of the throttle valve actuator 21.

The operation of the individual intake port carburetion system 10 will be described hereinbelow under the following conditions: (a) general driving, (b) starting and idling, (c) acceleration and power and (d) deceleration and fuel cut off.

The general operation of the invention under normal straight-away driving conditions may be described as follows. By use of the foot pedal 89 the engine operator selectively adjusts the positioning of the piston member 80 of the air-fuel distributor 24 and thus limits the open positions of the air meter element 40 and the fuel metering element 64. The vacuum condition which exists in the air intake manifold 12 acts upon the air metering element 40 to maintain an open or leftward position as viewed in FIG. 3, along with the fuel metering element 64, at which position the left end 69 of the fuel meter element 64 abuts the stop provided by the wall 81 of the piston member 80. The simultaneous movement of air metering element 40 and fuel metering element 64 to their limiting positions provides predetermined compatible area schedules for both air and fuel flows for controlling the air-fuel ratio of the admixture being supplied to the respective supply pipes 13a-13 through conduits 78a-78d, and this is particularly true when both the air and the fuel flowing through their respective metering elements 40 and 64 maintain substantially constant pressure differentials thereacross. The individual throttle valves 14a-14d are positioned automatically by the automatic throttle valve actuator 21 to maintain a predetermined vacuum condition in the intake air manifold 12 (say, 8 inches H_2O). The operation of the actuator 21 is under the control of the vacuum controller 120, which communicates chamber 91 of the actuator 21 with either manifold vacuum or after-throttle vacuum or (as is most generally the situation) by a level of vacuum between manifold and after-throttle vacuum (as a consequence of the "hunting" action of the vacuum controller plunger 136).

The after-throttle vacuum is obtained from the pressure taps or after-throttle sensing conduits 150a-150d which are drilled respectively into the supply pipes 13a-13d downstream of the throttle valves 14a-14d. As a result of the common conduit 149, the pressure taps 150a-150d provide an average after-throttle vacuum signal. Since periodic vacuum variations

are occurring in all of the intake ports A-D as a consequence of the restriction to air flow caused by the individual throttle valves 14a-14d and as a consequence of the periodic and sequential operation of the intake valves of the engine 11 (one of which is indicated at reference numeral 25 in FIG. 1), during the intake strokes of their respective pistons there is produced not only periodic intake air flows into the engine cylinders but also periodic flows of primary air-fuel admixture in the lines 78 which communicate the air-fuel distributor 24 with the supply pipes 13a-13d.

The vacuum control 120, as noted, operates in conjunction with the automatic throttle valve actuator 21 to maintain the manifold vacuum at a substantially constant level. The primary air-fuel dividing and distributing function of the air-fuel distributor 24 is dependent upon the reaction of the individual throttle valves 14a-14d and the periodic opening of the intake valves of the engine 11 to produce periodic variations in vacuum in the intake ports A-D. The pressure taps 150a-150d sample this varying vacuum and the vacuum which they provide in turn is the motivating force in the automatic throttle valve actuator 21 which is used for opening and closing the individual throttle valves 14a-14d. The action of the differential areas of the motive surfaces 99 and 100 of the piston member 97 ensures that the individual throttle valves 14a and 14d are adjusted toward the open position thereof only to a degree required to maintain a substantially constant vacuum (for example, 8 inches H₂O) in the air intake manifold 12.

b. Starting and Idling

Before the engine 11 is cranked the internal pressure of the entire carburetion system 10 is substantially balanced at atmospheric pressure. The air meter element 40 of the air-fuel distributor 24 is in a closed position, that is, the rightward position thereof as shown in FIG. 3. The fuel meter element 64 is also in its closed position, blocking the flow of fuel from the fuel chamber 54 to the primary air chamber 56.

The individual throttle valves 14a-14d may or may not be in a closed position. By "closed position" is meant the position of maximum restriction or air pressure drop thereacross, for any given air flow rate, whereas "open position" is meant the position of minimum restriction or pressure drop. The angle through which the throttle valves 14a-14d can be moved from full open to full closed position depends upon individual engine design and may be in the order of about 60°-75°. In their closed positions, however, the throttle valves 14a-14d do not completely block air flow through the supply pipes 13a-13d but merely present a greater restriction to flow than obtains when the throttle valves are in their open positions. Thus even in the closed positions of the throttle valves 14a-14d there is some communication between the intake ports A-D and the air intake manifold 12 through the supply pipes 13a-13d in the illustrated embodiment of the engine 11.

During idling of the engine 11 the throttle valves 14a-14d are substantially in their closed positions, that is, the positions of maximum restriction to air flow. If the engine was previously stopped while it was operating at idle, the throttle valves remain in their closed positions, since the chambers 91 and 94 of the throttle valve actuator 21 fairly rapidly rise to atmospheric pressure, thereby providing a pressure balance within the actuator 21.

On the other hand, if the engine 11 is stopped while it is operating at a speed above idle with the throttle valves 14a-14d in a somewhat open position, the valve will generally remain in that position during the entire period that the engine is at rest.

The position which the throttle valve 14a-14d will assume just as soon as cranking begins depends upon the level of vacuum created by cranking at the critical locations in the carburetion system 10 as a consequence of the speed at which the starter motor is able to crank the engine. Conventional electric starter motors are incapable of turning the ordinary engine over at a speed which is capable of producing substantial vacuum conditions in the carburetion system. Even relatively slow cranking of the engine does produce some vacuum in the

carburetion system, however, as will be understood by those skilled in the art.

As soon as cranking of the engine begins, therefore, a vacuum condition will be produced in the supply pipes 13a-13bq, and therefore in the air intake manifold 12. As soon as the level of vacuum in the manifold 12 rises to the "minimum vacuum" the air meter element 40 will be moved leftwardly to permit air to be induced through the air inlet opening 23 of the air-fuel distributor 24, assuming that the operator has depressed the foot pedal 89, thereby moving the stop 81 of the air-fuel distributor 24 leftwardly as viewed in FIG. 3 to enable the air meter element 40 to move leftwardly. If the operator has depressed the foot pedal 89 only slightly, then mere cranking of the engine will cause the air meter element or baffle plate 40 to move leftwardly a distance sufficient so that the end 69 of the fuel meter element 64 abuts the stop 81. Of course, if the operator depresses the pedal 89 more than only slightly, then a mere "minimum vacuum" condition in the manifold 12 will not cause movement of the air metering element 40 to its limiting position in an open direction, that is, a position at which the end 69 of the fuel meter element 64 abuts the stop 81, since the air meter element 40 will only move leftwardly a distance sufficient to "open" a small number of the passageways 32 formed in the perforate inner sleeve 31.

In view of the foregoing and in further explanation thereof, assume that the carburetion system 10 is designed to maintain a vacuum level of about 8 inches H₂O under normal operating conditions. The spring 48 is selected to permit the air meter element 40 to open at some manifold vacuum condition less than 8 inches, say about 6 inches. This level of vacuum which is required to move the air meter element to a minimum open position is referred to herein as "minimum vacuum." Upon cranking of the engine the chamber 94 of the throttle valve actuator 21 will then be subjected to that minimum vacuum condition. This will cause the piston rod 20 to move leftwardly to close the throttle valve 14a-14d, since any vacuum condition in chamber 94 will have the effect of closing the throttle valves 14a-14d unless the vacuum level in the chamber 91 is at least twice as great as the vacuum level in chamber 94.

During cranking of the engine the plunger 136 of the vacuum controller 120 will be located at a position below that in which it is shown in FIG. 4 since manifold vacuum will only be about 6 inches assuming, for example, that this is the "minimum" vacuum required to open the air meter element 40. Thus the port 129 will be in communication with port 144, thereby subjecting chamber 91 of the throttle valve actuator 21 to after-throttle vacuum.

Assuming, as is the case in the illustrated embodiment, that the throttle valves 14a-14d cannot close off the supply pipes 13a-13 sufficiently to restrict the flow of air therethrough to develop an after-throttle vacuum which is at least twice as great as manifold vacuum, the piston rod 20 will be biased leftwardly to maintain the throttle valves 14a-14d in a closed position, if they were closed when cranking of the engine began, or to move the throttle valves to their closed positions if they were open as cranking began.

Under normal cranking conditions, therefore, manifold vacuum is less than design level, (that is, less than 8 inches of water), and the air metering element 40 will move leftwardly far enough to "crack" some of the air passageways 32 and the fuel meter element 64 will move leftwardly the same distance to enable fuel to flow from the fuel chamber 54 to the primary air chamber 56. Primary air, that is, air which flows into the primary air chamber 56 via the bores 38, the chamber 75 and the port 72, mixes with the fuel and the primary air chamber 56 and is induced through the pipes 78 to the intake ports A-D on the downstream or intake port sides of the individual throttle valves 14a-14d. Since the intake valves 25 open sequentially the fuel-primary air mixture is induced through the pipes 78 sequentially in accordance with the firing order of the engine 11, as will be understood by those skilled in the art.

After the engine has fired the speed of the engine will increase to the operating speed permitted by the amount of fuel being metered by the fuel meter element 64.

As engine speed increases to idling speed (or to the speed permitted by the degree of depression of the foot pedal 89) the increased rate of ingestion of air into the engine 11 will have the effect of increasing the manifold vacuum above "minimum" vacuum and up to the level of manifold vacuum at which the system 10 is designed to operate.

Assuming that the position of the pedal 89 is held constant, the throttle valve 14a-14d will be moved by the throttle valve actuator 21 as required to maintain manifold vacuum at design level (8 inches of water in the exemplary embodiment). The manner in which this occurs will now be explained in detail.

Assume that as the engine is running the speed drops off slightly so that actual manifold vacuum drops to a level which is less than design. The plunger 136 of the vacuum controller 120 will then move to a position which is lower than the position thereof shown in FIG. 4 and will communicate after-throttle vacuum to the chamber 91 of the throttle valve actuator 21. As noted hereinabove, in the exemplary embodiment of the engine 11 after-throttle vacuum is always greater than twice manifold vacuum by virtue of the size and positional arrangement of the throttle valve 14a-14d. Thus, whenever the chamber 91 is subjected to after-throttle vacuum the piston rod 20 will move rightwardly to cause the throttle valve 14a-14 to move more toward the wide open positions thereof.

It should be repeated that it is not necessary to the principles of the present invention that after-throttle vacuum be at least twice as great as manifold vacuum. The exemplary embodiment of the engine 11 merely is designed to produce that result and therefore the various motive surfaces of the throttle-valve actuator 21 are sized to cause movement of the throttle valve 20 rightwardly to open the throttle valves 14a-14d whenever the chamber 21 is subjected to a level of vacuum at least twice as great as manifold vacuum or the vacuum which obtains in chamber 94. Thus the after-throttle vacuum is merely a motivating vacuum which is used to assist in the operation of the throttle valve actuator 21 since some source of vacuum higher than manifold vacuum which exists in chamber 94 is utilized as an operating medium.

As the piston rod 20 moves rightwardly to open the throttle valves 14a-14d the amount of secondary air flowing through the air inlet opening 23, the air intake manifold 12 and the supply pipes 13a-13d will increase due to the reduction in the restriction to air flow provided by the throttle valves 14a-14d. This increase in flow rate of air through the intake air opening 23 and the manifold 12 will result in an increase in vacuum in the manifold 12 as well as in the chamber 120b of the vacuum controller 120. As manifold vacuum rises back to design level (8 inches H₂O in the exemplary embodiment) the plunger 136 of the vacuum controller 120 will move upwardly. If manifold vacuum is substantially 8 inches H₂O the plunger 136 will rise to the position thereof shown in FIG. 4. If manifold vacuum should be greater than design level, the plunger 136 will move upwardly beyond the position thereof shown in FIG. 4, thereby communicating port 131 with port 129, thereby subjecting chamber 91 of the throttle valve actuator 21 to manifold vacuum. As soon as this occurs, that is, as soon as chambers 94 and 91 are both subjected to manifold vacuum, the piston member 97 and the piston rod 20 will begin to move leftwardly to cause the throttle valves 14a-14d to move toward the closed position thereof. This movement of the throttle valves 14a-14d toward their closed positions will have the effect of reducing the level of manifold vacuum and lowering the plunger 136 toward the position thereof shown in FIG. 4.

It is thus apparent that the plunger 136 will generally "hunt" above and below the "neutral" position thereof shown in FIG. 4. As manifold vacuum becomes less than design level, the plunger 136 will move downwardly from the position

thereof shown in FIG. 4 to communicate after-throttle vacuum with the chamber 91 to cause the throttle valves 14a-14 to move toward the open positions thereof. If the manifold vacuum rises above design level, the plunger 136 will move upwardly from the position thereof shown in FIG. 4 to communicate chamber 91 with manifold vacuum, thus causing the piston member 97 and the piston rod 20 to move the throttle valves toward the closed positions thereof.

It is apparent from the foregoing that when the chamber 91 is subjected to after-throttle vacuum, the throttle valves 14a-14 will be moved toward their open positions. When the chamber 91 is subjected to manifold vacuum the throttle valves 14a-14d will be moved toward their closed positions.

Now assume that the vehicle in which the engine 11 is mounted is being driven along an undulating road while the foot pedal 89 is maintained in a stationary position. If the vehicle travels to a downgrade the speed of the engine 11 will, of course, be increased. This increase in engine speed will have the effect of increasing manifold vacuum say, for sample, to about 10 inches H₂O. This increase in manifold vacuum, results from the increase in the flow rate of air being ingested into the engine 11 without a commensurate increase in the total open air of the air passageways 32 through which the air flows into the manifold 12 (and thus with an increased pressure loss of the air as it enters the manifold 12). This increase in manifold vacuum causes the plunger 136 of the vacuum controller 120 to move upwardly from the position thereof shown in FIG. 4, whereby the chamber 91 of the throttle valve actuator 21 is subjected to manifold vacuum. This has the effect of moving the throttle valves toward the closed positions thereof.

The throttle valves 14a-14d will continue to move toward their closed positions until the manifold vacuum decreases to about 8 inches H₂O, whereupon the plunger 136 of the vacuum controller 120 will again move to approximately the neutral position thereof shown in FIG. 4. It will be appreciated that this closing of the throttle valve 14a-14d sufficient to maintain the manifold vacuum at design level will also have the effect of maintaining constant power of the engine.

Of course, the position of the air metering element 40 and the fuel meter element 64 has been maintained in a constant position due to the constant position of the foot pedal 89. Before the throttle valves 14a-14d move toward the closed positions thereof the fuel-air ratio may become slightly different than the design ratio since the flow rate of secondary air is greater than that which is required to maintain manifold vacuum at design level. As the throttle valves 14a-14d are moved quickly toward the closed positions thereof, however, the optimum or design fuel-air ratio is again achieved as manifold vacuum is again reduced to the design level of 8 inches H₂O.

Assume now that the vehicle is being driven on an upgrade in the road. With the foot pedal 89 maintained stationarily the reduction in engine speed (due to the increased load) results in a decrease in the flow rate of air being ingested into the engine 11. This reduction in flow rate has the effect of reducing manifold vacuum thereby causing the plunger 136 of the vacuum controller 120 to move downwardly from the position thereof shown in FIG. 4. Ports 144 and 129 are thereby placed in communication with one another, the effect of which is to subject chamber 91 of the throttle valve actuator 21 to after-throttle vacuum. The piston member 97 is thereupon moved rightwardly as viewed in FIG. 5 causing the throttle valve 14a-14 to move toward the open positions thereof.

As the throttle valves 14a-14d are moved toward their open positions the restrictions to air flow caused thereby are reduced, thus permitting the engine 11 to ingest a greater quantity of air. This, of course, increases manifold vacuum back to 8 inches, the design value, and maintains constant power output of the engine 11 and tends to maintain a substantially constant fuel-air ratio.

From the foregoing it will be appreciated that the throttle valves 14a-14d will automatically move toward the open posi-

tions thereof when the vehicle is running up a sloping incline and will move toward their closed positions when the vehicle is running down a sloping incline without any adjustment whatsoever in the foot pedal 89. Consequently, the power output of the engine as well as the fuel-air ratio is maintained at a more uniform of constant level, as the vehicle is driven over an undulating road, than is obtainable in conventional carburetion systems of the prior art.

c. Acceleration and Power

Assume now that the driver of the vehicle wishes to increase the speed of the engine. The foot pedal 89 is depressed, thereby moving the stop 81 of the air-fuel distributor 24 leftwardly.

At the time the foot pedal 89 is depressed the end 69 of the fuel meter element 64 was in abutting relation with the stop 81 since the manifold vacuum of 8 inches was more than enough to overcome the rightward bias of the spring 48 which, by itself, is sized to provide a "minimum vacuum" of only 6 inches. Thus as soon as the stop 81 is moved leftwardly the air meter element 40 also moves slightly leftwardly.

As soon as the air meter element 40 moves leftwardly the manifold vacuum falls below the design level of 8 inches but only to the minimum vacuum level of 6 inches, that is, the vacuum required to maintain the air meter element 40 in an open position against the bias of spring 48. This reduction in manifold vacuum occurs, of course, because of the additional air metering area resulting from the leftward movement of the air meter element 40 to uncover or open more of the air passageways 32.

Leftward movement of the air meter element 40 increases the flow rate of air being ingested into the engine 11 and also moves the fuel meter element 64 leftwardly to increase the flow rate of liquid fuel into the engine. Furthermore, the reduction in manifold vacuum causes the plunger 136 of the vacuum controller 120 to move downwardly, thereby communicating chamber 91 of the automatic throttle valve actuator 21 with after-throttle vacuum, causing the throttle valves 14a-14d to move toward their open positions.

The rate at which the throttle valves 14a-14d move toward their open positions cannot exceed a rate of throttle opening that would reduce the after-throttle vacuum below approximately twice manifold vacuum by reason of the differential area reaction of the throttle valve actuator 21. Thus if the throttle valves 14a-14d were to open so rapidly that after-throttle vacuum fell to a level below two times manifold vacuum, then the piston member 97 of the throttle valve actuator 21 would begin to move leftwardly to cause the throttle valves 14a-14d to move back toward their closed positions. The result is, of course, that the throttle valves 14a-14d are not moved so rapidly by the actuator 21 that after-throttle vacuum falls below two times the manifold vacuum.

As the throttle valves 14a-14d move steadily toward a more open position and as the fuel meter element 64 moves steadily leftwardly, the air being ingested into the engine 11 increases upon increase in engine speed, and consequently the air meter element 40 continues to move steadily leftwardly at a rate of movement sufficient to maintain a "minimum" vacuum condition in the manifold 12 until the end 69 of the fuel meter element 64 again comes into abutting engagement with the stop 81. When this occurs, of course, the vacuum controller 120 and the throttle valve actuator 21 will continue to operate to open the throttle valves 14a-14d until manifold vacuum again rises to design level, that is, 8 inches of water. Steady state operation of the engine 11 at a higher speed and load is thereupon achieved when manifold vacuum again rises to this design level and the air meter element 40 and the fuel meter element 64 are again restricted against further leftward movement.

d. Deceleration and Fuel Cutoff

Assume now that the driver of the vehicle wishes to decrease the speed of the engine. The foot pedal 89 is permitted to rise by virtue of the spring 89a, thereby causing the stop 81 of the air-fuel distributor 24 to be moved rightwardly.

This rightward movement of the stop 81 causes the fuel meter element 64 and the air meter element 40 to move rightwardly. As a consequence of this movement of the air metering element 40 toward the closed position thereof the level of vacuum in the manifold 12 is increased and the flow rate of liquid fuel to the engine 11 is decreased.

An increase in manifold vacuum, of course, has the effect of moving the throttle valves 14a-14d toward the closed positions thereof, thereby reducing the flow rate of air being ingested into the engine 11 and lowering the level of vacuum in the manifold 12. It is noted that the air meter element 40 and the fuel meter element 64 move toward their closed positions before the throttle valves 14a-14d move toward their closed positions. This initial movement by the air and fuel meter elements followed by a change in throttle valve position maintains close control of fuel-air ratio and good distribution of fuel by maintaining the periodic intake flows of primary air and fuel from the air-fuel distributor 24 through the supply pipes 78 to the intake ports A-D not only during deceleration but during all other periods of operation as well. The positioning of the throttle valves 14a-14d by means of the vacuum controller 120 and the automatic throttle valve actuator 21, in place of manual control by the vehicle operator, provides for optimum use of the principle of utilizing individual throttle valves in conjunction with means for controlling the fuel-air ratio and dividing and distributing primary air and fuel to the individual intake ports A-D.

The fuel metering element 64 is constructed and arranged so that, during shutdown periods, the flow of liquid fuel into the primary air chamber 56 is substantially completely stopped. As a consequence, the escape of fuel vapors during shutdown is prevented. The bleed line 63 leading back to the fuel tank 59 enables the pressure regulator 61 to bleed down during periods of engine shutdown so that during such periods when the engine is not in use, fuel is not trapped between the pressure regulator 61 and the fuel metering element 64. The elimination of fuel evaporation by virtue of the present invention assists in the prevention of air pollution.

Control of engine speed by the operator by virtue of the actuation of the foot pedal 89 is accompanied with a desirable control feedback pressure sensation by the action of the piston member 80 of the air-fuel distributor 24 and the reaction of the air and fuel metering elements 40 and 64 against the stop or abutment 81 under steady state operation as well as during acceleration and deceleration periods. This varying pressure sensation results from the following. To increase the speed or load of the engine, the operator's action in moving the sliding piston 80 leftwardly as shown in FIG. 3 against the vacuum in the air intake manifold 12 acting on the right side of the piston 80 requires a force which is greater than that which is required to hold the piston 80 at a steady state condition. Thus the force reaction on the stop 81 constitutes a counter balancing effect between any excess moving force acting on the air metering element 40 to move the same leftwardly and the vacuum force acting on the stop 81 to move the same rightwardly.

The source of the excess force tending to move the air meter element 40 leftwardly results from the fact that the "minimum" vacuum required to move the air metering element 40 leftwardly (6 inches of water in the illustrated embodiment) is less than the vacuum in the air intake manifold 12 as established by the vacuum controller 120 and the automatic throttle valve actuator 21 during steady state operation (8 inches in the water in the illustrated embodiment).

This excess force acting in a leftward direction on the air meter element 40 tends to maintain contact of the end portion 69 of the fuel metering element 64 against the stop 81 without "bounce" unless the operator requires rapid acceleration, in which event the fuel metering element 64 loses contact with the stop 81 until equilibrium is restored as steady state operation is approached.

On the other hand, the contact force of the stop 81 on the fuel metering element 64 aids in the rightward movement of

the air and fuel metering elements 40 and 64 during deceleration and shutdown. The engine operator has a light pressure reaction from the foot pedal 89 which increases if the operator attempts to accelerate at a greater rate than the air metering element 40 can respond in maintaining contact of the fuel metering element 64 with the stop 81. The motive area of the sliding piston member 81 relative to the motive area of the air metering element 40 is selected to provide optimum operator comfort, desirable control pressure feedback characteristics and compatibility with the return action of the spring-biased foot pedal 89.

It is noted that the disposition of the engine 11 and the carburetion system 10 with respect to the vertical is merely illustrative and that both the engine 11 and the carburetion system can assume any other disposition with respect to the vertical.

For example, the arrangement illustrated in the drawing may be rotated by 90° whereby the valve stem of the intake valve 25 would extend substantially vertically, along with the axis of the fuel metering element 64. In the event of such disposition of the engine 11 and the carburetion system 10 whereby the air and fuel metering elements 40 and 64 move in a vertical rather than a horizontal direction, the weight of the air metering element 40, the rods 39 and other pertinent components are taken into account in determining the constant bias of the air and fuel metering elements 40 and 64 toward the closed positions thereof, in addition to the force of the spring 48. Depending upon the manifold vacuum desired (for example, 8 inches of water) and the air and fuel metering elements 40 and 64 may be constructed of materials having given masses and the spring 48 may also be selected so as to have a predetermined k factor or spring rate.

In connection with the spring 48, it may be desirable to have a constant spring rate. Constant rate springs have a substantially uniform rate of compression per unit of force.

It is not necessary that the spring 48 have a constant spring rate, however, to provide satisfactory operation. If the spring rate is not constant more force is required to move the air meter element 40 leftwardly a given distance the further that the element is moved from the closed position thereof.

An engine is able to accelerate at a greater rate at high speed than at low speed. Consequently, the inherent tendency of the engine 11 would be to accelerate at a greater rate when the air meter element 40 is positioned more toward the extreme leftward than the extreme rightward position thereof. As the air meter element 40 is moved leftwardly, however, the k factor of the spring 48 increases (assuming that the spring rate is not constant) and thus the air meter element 40 will have a tendency to move leftwardly more slowly when the engine is operating at high speed than at low speed. This will, of course, tend to maintain a more uniform fuel-air ratio during acceleration at high speed.

Referring to FIG. 6 another embodiment of a fuel metering element is indicated therein at reference numeral 64', which differs principally from the fuel metering element 64 in that, instead of having a tapered outer wall, the outer wall thereof is cylindrically shaped but has a plurality of axially extending grooves 64" formed therein in radially angularly spaced relation. As the fuel metering element 64' is adjusted axially in the air-fuel distributor 24 the grooves 64", which are blocked when the engine 11 is shut down, become increasingly unblocked at higher engine speed to enable an increasingly higher flow rate of fuel from the fuel chamber 54 to the primary air chamber 56 through the reduced diameter passageway 57.

Although minor modifications might be suggested by those versed in the art, it should be understood that I wish to embody within the scope of the patent warranted herein all such modifications as reasonably come within the scope of my contribution to the art.

What I claim is:

1. An individual intake port carburetion system for delivering an air-fuel mixture to the intake ports of a multi-cylinder internal combustion engine comprising an air manifold,

a plurality of supply pipes each communicating at one end with said air manifold and at the other end with a respective one of said intake ports, individual adjustable valves located respectively in said supply pipes, means including a throttle arm interconnecting said throttle valves for simultaneous adjustment thereof, means forming a primary air chamber, means for directing air into said air manifold and said primary air chamber and including means forming an air inlet opening, a plurality of primary air-fuel conduits each communicating at one end with said primary air chamber and at the other end with a respective one of said supply pipes downstream of its corresponding throttle valve, means including an adjustable fuel meter means communicating with said primary air chamber and adapted for connection to a source of pressurized fuel, adjustable limiting means operatively connected to said fuel meter means for selectively limiting the maximum flow rate of fuel to said primary air chamber, air meter means including means communicating with said air inlet opening, operatively connected to said fuel meter means and responsive to an increase in the flow of air into said manifold for urging said fuel meter means to an increasingly open position to the limit afforded by said adjustable limiting means, and automatic throttle valve control means including a pressure responsive actuator means having means operatively connected to said throttle arm and means communicating with said air manifold for opening and closing said throttle valve in response to variations in the level of vacuum in said air manifold to maintain the vacuum condition in said air manifold at a constant level.

2. The invention as defined in claim 1 wherein said air meter means comprises an air meter element adjacent said air inlet opening, and means for biasing said air meter element toward a closed position with respect to said air inlet opening to require a minimum level of vacuum in said manifold, during operation of the engine, sufficiently high to urge said air meter element away from said closed position.

3. The invention as defined in claim 1 wherein said air inlet opening communicates said air manifold and said primary air chamber with atmospheric air.

4. The invention as defined in claim 1 wherein said adjustable limiting means comprises means forming a cylinder, one end of which communicates with said air manifold and the other end of which is open to atmosphere, piston means slidable in said cylinder, and manually operable means for selectively positioning said piston in said cylinder, said piston means comprising means forming a shoulder in abutting alignment with said adjustable fuel meter means for providing a limiting stop therefor.

5. The invention as defined in claim 1 wherein said adjustable fuel meter means comprises means forming a fuel chamber communicating with said primary air chamber, means forming a passageway communicating said fuel chamber and said primary air chamber, and a valve member movable in opposite directions in said passageway for alternatively increasing and decreasing the flow of fuel from said fuel chamber to said primary air chamber.

6. The invention as defined in claim 5 wherein said valve member comprises an elongated rod having an axially tapered outer wall.

7. The invention as defined in claim 5 wherein said valve member comprises an elongated rod having first and second portions, said first portion having longitudinally extending grooves of varying cross-sectional area formed in the outer wall thereof for metering fuel, said second portion having a

circumferentially continuous outer wall for blocking flow of fuel during shut-down.

8. An individual intake port carburetion system for delivering an air-fuel mixture to a multi-cylinder engine comprising an air manifold having means forming an air inlet opening, 5 a plurality of supply pipes individually communicating each of the intake ports of the engine with said air manifold, air meter means in said air inlet opening movable between open and closed positions in response to variations in the 10 flow rate of air through said air inlet opening, adjustable means for limiting the movement of said air meter means toward the open position thereof, fuel supply means including means adapted for connection to a source of pressurized liquid fuel and connected to 15 said supply pipes for delivering fuel under pressure thereto, said fuel supply means including adjustable means connected to said air meter means for varying the flow rate of said liquid fuel to said supply pipes as a function of 20 variations of the flow rate of air through said air inlet opening, individual throttle valves located respectively in said supply pipes and interconnected for joint adjustment, and means responsive to variations in the level of 25 vacuum of air in said air manifold for adjusting said throttle valves to tend to maintain said vacuum level at a constant value.

9. A carburetion system for an internal combustion engine comprising means including supply pipe means and selectively adjustable air and fuel metering means communicating with said supply pipe means for directing a flow of air-fuel admixture to the intake ports of the engine, 35 adjustable throttle valve means in said supply pipe means, and pressure responsive actuator means for sensing variations in the vacuum in said supply pipe means upstream of said throttle valve means and for automatically adjusting said throttle valve means in response to said variations to maintain a constant level of vacuum upstream of said throttle valve means regardless of the position of adjustment of said air and fuel metering means, 40 said pressure responsive actuator means comprising a pressure cylinder, a piston slideable in said pressure cylinder for operative connection to said throttle valve means and means communicating said supply pipe means with said pressure cylinder on one side of said piston, 45 said pressure responsive means further comprising vacuum control means having means forming a vacuum chamber, a vacuum control port communicating with said vacuum chamber and with said pressure cylinder on an opposite side of said piston and first and second operating ports communicating with said vacuum chamber and with said supply pipe means on the upstream and downstream sides of said throttle valve means, respectively, and means in said vacuum chamber operable in response to the difference in the 50 level of vacuum between said first and second operating ports for alternatively communicating said first and second operating ports with said vacuum control port when the level of vacuum in said supply pipe means upstream of said throttle valve means falls below and rises 55 above a predetermined level.

10. For use in a multi-cylinder internal combustion engine, an individual intake port carburetion system comprising supply pipe means connected to the intake ports of the engine, air manifold means having an air intake opening for receiving and directing secondary air to said supply pipe means, 70 adjustable throttle valve means in said supply pipe means, primary air-fuel distributor means including means forming a primary air intake port, a fuel intake port for receiving liquid fuel under pressure and a pri-

mary air-fuel mixing chamber communicating with said primary air intake port and said fuel intake port, fuel meter means situated between said fuel intake port and said mixing chamber and movable between first and second positions for alternatively increasing and decreasing the rate of flow of fuel to said mixing chamber, air meter means including a movable baffle in said air intake opening and arranged for joint movements with said fuel meter means, said baffle being movable in response to the flow rate of air flowing through said air intake opening for urging said fuel meter means toward said open position thereof and for changing the level of vacuum in said air manifold means, and adjustable stop means for manually selectively limiting movement of said fuel meter means towards said first position thereof and for positively moving said fuel meter means toward said second position thereof, primary air-fuel conduit means communicating said mixing chamber with said supply pipe means on the intake port side of said throttle valve means, and vacuum control means for maintaining the level of vacuum in said air manifold means at a constant value including means for sensing the level of vacuum in said air manifold means and for adjusting said throttle valve means in response to variations in the level of vacuum in said manifold means.

11. The invention as defined in claim 10 wherein said supply pipe means comprises individual supply pipes for each of the intake ports and said primary air-fuel conduit means comprises individual conduits corresponding in number to the number of supply pipes and communicating with their respective supply pipes between said intake ports and said throttle valve means.

12. The invention as defined in claim 10 wherein said primary air-fuel mixing chamber is cylindrically shaped and said primary air-fuel conduits open to said mixing chamber in radially angularly spaced relation about the axis of said chamber.

13. The invention as defined in claim 11 and including means for delivering fuel under constant pressure to said fuel meter means during engine operation and for blocking fuel flow to said fuel meter means during shut-down and bleeding down the fuel supply pressure.

14. An individual intake port carburetion system for delivering an air-fuel mixture to the intake ports of a multi-cylinder internal combustion engine comprising an air manifold,

a plurality of supply pipes each communicating at one end with said manifold and at the other end with a respective one of said intake ports, individual adjustable throttle valves in each of said supply pipes, means including a throttle arm interconnecting said throttle valves for simultaneous adjustment thereof, means forming a primary air chamber, means for directing air into said air manifold and said primary air chamber and including means forming an air inlet opening,

a plurality of primary air-fuel conduits each communicating at one end with said primary air chamber and at the other end with a respective one of said supply pipes downstream of its corresponding throttle valve, means including an adjustable fuel meter means communicating with said primary air chamber and adapted for connection to a source of pressurized fuel,

adjustable air meter means including means communicating with said air manifold and operatively connected to said fuel meter means, adjustable limiting means operatively connected with said fuel meter means and said air meter means for selectively limiting the maximum flow rate of fuel to said primary air chamber,

21

said air meter means being responsive to the flow of air through said air inlet opening for urging said fuel meter means toward an increasingly open position to the limit afforded by said adjustable limiting means, and automatic throttle valve control means including pressure responsive actuator means having means operatively con-

22

nected to said throttle arm and means communicating with said air manifold for opening and closing said throttle valves in response to variations in the level of vacuum in said air manifold to maintain the vacuum condition in said air manifold at a constant level.
